UNITED STATES PATENT OFFICE.

WALTER L. ASHMORE, OF MACON, GEORGIA.

DEVICE FOR FINISHING CONCRETE PAVEMENTS.

Application filed April 15, 1922. Serial No. 553,008.

To all whom it may concern:

Be it known that I, WALTER L. ASHMORE, a citizen of the United States, residing at Macon, in the county of Bibb and State of Georgia, have invented certain new and useful Improvements in Devices for Finishing Concrete Pavements; and I do hereby declare the following to be a full, clear, and exact description of the invention, such as will enable others skilled in the art to which it appertains to make and use the same.

This invention relates to devices for tamping and finishing concrete pavements, and more particularly to an improvement upon the device shown and described in Patent No. 1,364,604 issued to me and H. R. Powell, jointly, on January 4, 1921.

The primary object of my invention is to provide a simple, inexpensive and efficient device of the character referred to, in which the vibrations of an engine or motor are utilized in producing the desired tamping effect upon freshly laid soft, plastic concrete or upon soft plastic concrete upon which has been spread or cast a thin layer of coarse aggregate as used in the construction of road-beds and street pavements or the like.

The invention will first be hereinafter more particularly described, with reference to the accompanying drawings, which are to be taken as a part of this specification, and then pointed out in the claims at the end of the description.

In said drawings, Fig. 1 represents a front view of a machine or apparatus embodying my invention;

Fig. 2 is a plan view of the same;

Fig. 3 is a side elevation;

Fig. 4 is a fragmentary detail view of a broken away portion of the machine; and

Fig. 5 is a detail fragmentary view illustrating the pivotal connection between the pressure-plate and one of the roller-supporting levers.

Referring to said drawings, in which the same reference characters are used to denote corresponding parts in different views, the letter A denotes a pressure-plate of substantially rectangular form arranged between rollers B, B, and adapted to be moved over the surface of the paving and have imparted thereto the desired tamping effect, by means of a vibrator mounted thereon, either an air or gas engine or electric motor, adapted to produce a vibrating pressure.

As shown, arched flat metal or leaf springs

C, C, are secured to said pressure-plate, one upon each side thereof, the ends of the springs being bolted to side bars or flanges a of the pressure-plate, and a motor M is mounted on said springs, each spring having an attaching device c bolted thereto and to the motor M, as shown more clearly in Fig. 4 of the drawings. The rollers B, B, may be formed or provided with axles or gudgeons having their bearings in the short arms d, d, of levers D, D, each fulcrumed on the pressure-plate by means of a depending arm d' which is apertured to receive the threaded end of a pivot bolt E secured in one corner of the pressure-plate A, the lever being held in place on the pivot-bolt by means of nuts e and e' screwed on said bolt on opposite sides of the lever. Said short arm d of each lever has secured thereto one end of a coiled or other suitable spring F, the other end of which is secured to an upright or standard G mounted on the pressure-plate, one at each end, said upright having a series of holes g therein for attaching the free end of the spring and adjusting it to increase or decrease the tension at will. These springs are adapted to raise the short arms of the levers D when the long arms thereof are free to swing downwardly, and thereby raise the rollers C, and lower the pressure-plate into working contact with the surface of the pavement, as hereinafter described.

The levers D and associated parts arranged on opposite sides of the pressure-plate, for raising and lowering the pressure-plate and the engine mounted thereon, are each a counterpart or duplicate of the other, so that a description of one will suffice as a description of the other. The arrangement is such that the two rollers are simultaneously raised or lowered by pulling a cord or chain which may extend either rearwardly or forwardly of the machine frame, regarding one roller as being arranged at the front and the other at the rear of the machine, as both front and rear are alike. In the form shown, an internal combustion engine M is mounted on the tamping bar or pressure-plate A, and a gasoline tank or reservoir m is supported on uprights H, each of which is connected to one of the uprights or standards G by means of a brace I. To each of said standards G is pivoted a swinging lever K, preferably of T-shaped form, having the longer arm thereof connected to a chain or

the surface of the concrete, whereby said rollers will be lowered and said pressure-plate raised by the pull upon said swinging lever.

5. A device for finishing concrete pavements and the like comprising a pair of rollers, a pressure-plate of substantially rectangular form arranged between said rollers, a vibrator mounted upon said pressure-plate, and means for pulling the device over the surface of the concrete and thereby raising the pressure-plate, together with springs for automatically raising the rollers and simultaneously lowering the pressure-plate when the pull upon the device is released.

6. A device for finishing concrete pavements and the like comprising a pair of rollers, a pressure-plate of substantially rectangular form arranged between said rollers, a vibrator mounted upon said pressure-plate, and means for pulling the device over the surface of the concrete and thereby raising the pressure-plate, together with springs for automatically raising the rollers and simultaneously lowering the pressure-plate when the pull upon the device is released; said pulling and raising and lowering means being operable from either front or rear of the machine.

7. In a device of the character described, a pressure-plate arranged between a pair of rollers each having its bearings in a pair of levers fulcrumed on said pressure-plate at one side thereof and extending toward the other side, said pressure-plate having means thereon for imparting a vibrating pressure to a mass of concrete on which it may rest, and having a pair of swinging levers mounted thereon and provided with short arms which extend in the same direction as said first mentioned levers, the long arms of the latter being flexibly connected with the short arms of said swinging levers so that movement thereof in either forward or backward direction will cause said rollers to be lowered, thereby raising said pressure-plate, together with means for automatically low-

ering the pressure-plate and thereby raising the rollers when the swinging levers are released.

50

8. In combination, a pressure-plate constructed of sheet metal in substantially rectangular form and having a vibrator thereon, said pressure-plate being arranged between two rollers which extend lengthwise thereof, each roller being journaled in a pair of levers fulcrumed on said pressure-plate, a swinging lever mounted on said pressure-plate near each end having cross-arms flexibly connected with said first named levers so that said rollers will be lowered and said pressure-plate simultaneously raised when said swinging levers are moved in either forward or backward direction, and means for automatically raising said rollers and lowering the pressure-plate when said swinging levers are released.

55

9. A device for finishing concrete pavements and the like, comprising a pressure-plate arranged between a pair of rollers and having a vibrator mounted thereon, each of said rollers having bearings on a pair of levers fulcrumed on said pressure-plate for raising and lowering the rollers and simultaneously lowering or raising the pressure-plate, a swinging lever carried by said pressure-plate near each end having a pull cord attached thereto, and flexible connections between said swinging levers and said roller-carrying levers, whereby both rollers are lowered and the pressure-plate raised by pulling upon said cord, whereby the device may be moved step by step over the surface of soft, plastic concrete under treatment, and means for raising the rollers and lowering the pressure-plate when the pull upon the cord is released.
